UNITED STATES PATENT OFFICE

WALKER W. McCARROLL, OF NEW HAVEN, CONNECTICUT

IMPLEMENT HEATER FOR ELECTROTYPE BUILDERS

Application filed April 27, 1929. Serial No. 358,472.

This invention relates to an improvement in heaters and particularly to heaters for heating the implements or tools employed by electrotype makers in building up and altering the wax forms from which electrotypes are made.

The object of this invention is to provide a simple and convenient heater of the class described constructed with particular reference to supporting the implements in convenient position for use and to providing ready drainage for the wax, which may be adhered to the implements when they are replaced in the heater.

With the above and other objects in view, my invention consists in a heater having certain details of construction and combinations of parts as will be hereinafter described and particularly recited in the claims.

20 In the accompanying drawings:

Fig. 1 is a top or plan view of a heater constructed in accordance with my invention, the implements or tools which it is designed to heat being shown by broken lines;

25 Fig. 2 is a view thereof in side elevation;

Fig. 3 is a longitudinal sectional view taken on the line 3—3 of Fig. 1;

Fig. 4 is a transverse sectional view taken on the line 4—4 of Fig. 2; and

30 Fig. 5 is a transverse sectional view corresponding to Fig. 4 but showing a modified form of heater adapted for steam.

In carrying out my invention as herein shown in Figs. 1 to 4 inclusive, I employ a 35 box-shaped body-member comprising a top-plate 10, integral front and rear end-walls 11 and 12 and integral side-walls 13 and 14. The front and rear end-walls 11 and 12 being extended downward to form respectively 40 plate-like supporting-legs 15 and 16 each of which terminates in an outturned horizontal flange 17 through which screws may be passed for securing the device to a work-bench.

45 Depending within the casing of the heater from the top-plate 10 thereof, are a series of cone-shaped skirts 18 which produce a series of conical sockets 19 having their larger diameter intersecting the upper surface of the 50 top-plate 10 and having their lower ends

opening through the underface 20 of the conical skirts 18.

Each of the sockets 19 above referred to is adapted to receive and support the conical head 21 of an electrotype builder's tool 55 (shown by broken lines in Figs. 1 and 4) which may be of any approved form and is provided at its upper end with right-angled shanks 22 terminating in handles 23 of wood or other heat-insulating material.

Extending longitudinally through the casing is a gas-burner tube 24 which is externally threaded at its rear end as at 25 for threaded engagement with the rear end-wall 12 of the said casing. The front end of the tube 24 extends through the front end-wall 11 of the casing and is there provided with the usual mixing-chamber 26 having the usual knurled mixture adjusting-ring 27 and carries a gas-cock 28 which controls the flow of gas into the 60 burner-tube 24.

The burner-tube 24 is as shown located to one side of the series of conical skirts 18 depending from the top-plate 10 and is formed with a series of ports 29 directed toward the 65 said skirts 18 and slightly upward so as to project the flame substantially crosswise of the casing and in the general direction of the series of conical skirts 18 before referred to.

The portion of the upper face of the top-plate 10 lying between the first of the series 70 of sockets 19 and the front end of the casing is slightly depressed as at 30 and is intersected by a series of vertical passages 31. The space 30 upon the top-plate 10 is designed to 75 receive such knives and other implements which are not suitable in form for being supported in the sockets 19. The passages 31 affording an upward egress from within the casing for the products of combustion which 80 serve to heat any implements that may be placed on the surface 30.

The rear end-wall 12 of the casing has secured to it by means of screws 32 a substantially L-shaped bracket 33 upon which 85 implements may be stored when not required for immediate use.

The front end-wall 12 and the side-wall 14 of the casing are each provided with a series of vent-openings 34 designed to permit the 100

lateral egress of the products of combustion and thus insure a substantially uniform temperature within the chambered interior of the said casing.

5 By locating the burner-tube 24 to one side of the series of tool-receiving sockets 19 the adhering wax melted from the heads 21 of the tools after they have been in service and restored to the sockets for further heating, 10 will drain out of the open bottom end of the said sockets without coming in contact with the said burner-tube 24 so that obnoxious smoke and the clogging of the gas-ports 29 in the said tube are avoided.

15 While I have shown and described herein a heating-element designed for using gas, it will be readily understood that the same may be replaced by an electrical or other heating-element.

20 In Fig. 5 I have shown an implement heater which generally corresponds to the structure shown in the preceding figures except that it is adapted to be heated by steam. For this latter purpose I provide a bottom- 25 plate 35 extending laterally between and formed integral with the front, rear and side walls 11, 12, 13 and 14, and also integrally connected to the lower ends of the skirts 18.

The provision of the bottom-plate 35 as 30 just above described, serves to form an enclosed steam-chamber 36 into which steam may be introduced from a supply-pipe 37 having a coupling 38, the threaded nipple 39 of which is threaded into and projects 35 through the side-wall 13 into the steam-chamber 36.

I claim:

1. As a new article of manufacture, a heater for independently-formed tools comprising a horizontal plate having one or more tool-receiving sockets intersecting its upper face and depending beneath the upper surface of the said plate and open at their lower ends; means for supporting the said plate; and a heater element located to one side of the sockets in position to radiate heat laterally against the same.

2. As a new article of manufacture, a heater for independently-formed tools comprising a horizontal plate having one or more socket-skirts depending from its underface, the said skirts having formed therein sockets opening through the upper face of the said plate and also opening through the lower end 55 of the said skirt; means for supporting the said plate in spaced relation above a supporting-surface; and a heater-element located to one side of the said skirts and adapted to radiate heat laterally toward the same.

60 3. As a new article of manufacture, a heater for independently-formed tools comprising a chambered casing consisting of a top-plate and two end-walls and two side-walls depending from the said top-plate; one or more socket-skirts depending from the said

top-plate between the said end- and side-walls and each formed with a vertical socket intersecting its lower end and the upper surface of the said top-plate; and a heater-element located to one side of the said socket-skirts in 70 position to radiate heat against the same.

4. A heater of the type described comprising a chambered casing consisting of a top-plate and two end-walls and two side-walls depending from the said top-plate, the said end-walls being extended downward below the bottom edge of the said side-walls to form supporting-feet; one or more socket-skirts depending from the said top-plate between the said end- and side-walls and each formed 75 with a vertical socket intersecting its lower end and the upper surface of the said top-plate; and a heater-element supported by the said end-walls and located to one side of the said socket-skirts in position to radiate heat 80 against the same.

5. As a new article of manufacture, a heater for independently-formed tools comprising a horizontal plate having one or more conical socket-skirts depending from its under-face and formed with vertical cone-shaped sockets having their larger-diameter upper ends opening through the top surface of the said plate and their smaller-diameter lower ends opening through the bottom of the said 90 skirts; and a heater-element located to one side of the said skirts and adapted to radiate heat laterally against the same.

6. As a new article of manufacture, a heater for independently-formed tools comprising a horizontal plate having one or more vertical implement-receiving sockets opening through its upper face and open at their lower ends; means for supporting the said plate; and heating means located to one side of and 100 out of line with the axes of the said sockets; whereby wax adhering to implements installed in the said sockets may readily drain therefrom.

In testimony whereof, I have signed this 110 specification.

WALKER W. McCARROLL.
